REFRIGERATOR CABINET INSULATION

Carl H. Nauert, Evansville, Ind., assignor to
Servel, Inc., New York, N. Y., a corporation of
Delaware

Application March 1, 1934, Serial No. 713,441

3 Claims. (Cl. 220—9)

This invention relates to household refrigerators, and more particularly to the cabinets of such refrigerators and insulation for such cabinets.

5 It is an object of the invention to provide insulation capable of being easily applied about a liner and with the insulation sealed against the passage of air or the like at the joints, thereby improving the insulating effect.

10 It is a further object of the invention to provide as a unit insulation for the top, bottom and sides of the cabinet, and a separate panel of insulation for the rear of the cabinet which rear panel is adapted to snugly engage the insulation for the top, bottom and sides of the cabinet.

15 Other objects and advantages will be apparent from the following description taken in connection with the accompanying drawings, wherein

20 Fig. 1 is a side elevation of a cabinet constructed in accordance with the present invention and having a portion of the side wall broken away to disclose the insulation and the liner about which the insulation is applied;

25 Fig. 2, a similar view of the rear of the cabinet;

Fig. 3, a similar view looking down upon the cabinet;

30 Fig. 4, a plan view of the insulation for the top, bottom and two sides of the cabinet prior to its application;

Fig. 5, an edge view of the insulation in Fig. 4 illustrating the manner of its application;

35 Fig. 6, an enlarged fragmentary detail of one rear corner of the insulation as applied;

Fig. 7, a vertical section through the insulation in its assembled relation, showing in broken lines the rear insulating panel;

Fig. 8, a section on line 8—8 of Fig. 7; and

40 Fig. 9, an enlarged fragmentary detail of one front corner of the insulation as applied.

Referring to the drawings, a refrigerator cabinet consists of an outer shell or casing 10 and an inner shell or liner 11 between which shells insulation is adapted to be applied for preventing heat transfer from the exterior to the interior of the cabinet or through the cabinet wall. The cabinet is of the type in which access to the food compartment defined by the interior of the liner may be had by means of a door 12. The food compartment is refrigerated by a cooling unit, not shown, disposed therein and connected to a refrigerating unit, not shown, located in the lower compartment of the cabinet, access to which lower compartment can be had by means

of a door 13. The casing 10 and the liner 11 are maintained in spaced relation by means of suitable framework.

Heretofore insulations of various types have been employed, one example being in the form of slabs of insulation between the liner and its enclosing casing of the cabinet. These slabs in some instances have been wrapped to render them impervious to the passage of air or moisture. With this construction the joints have 5 not been tight and heat leakage has occurred. In the present instance means is provided for sealing such joints and at the same time the same means is also utilized for facilitating the application of the insulation, consequently reducing the cost of labor involved.

10 In accordance with this invention five slabs of insulation are provided, one each for the top, bottom two sides, and rear of the cabinet, all of which are suitably wrapped in waterproof 15 paper or other material to render them impervious to the passage of moisture and air. As shown in Fig. 4, four wrapped slabs of insulation, 14, 15, 16, and 17 are provided, the slabs 14 and 15 serving to insulate respectively the top and 20 bottom of the cabinet, and the slabs 16 and 17 serving to insulate the two sides of the cabinet. The wrapping for these slabs of insulation is of 25 waterproof paper or the like for the purpose described above.

30 This wrapping for the several slabs may be applied in a number of ways, for example, one strip of material folded over upon itself, or two strips of wrapping material may be used. In either case one portion is of a length corresponding to 35 the total length of the four slabs 14, 15, 16, and 17 and forms when the insulation is in place an outer covering for the respective slabs. The other portion on the opposite side of the slab from the first mentioned portion is crimped at the joints 40 between the slabs to closely conform to the surface of the slab including the beveled ends of the same. The wrapping material is folded over at the front and rear edges as shown, and secured in place by cementing or the like. The 45 above described construction is nothing more than a single sheet or two spaced sheets of wrapping material between which the insulating slabs are confined, the wrapping material having its edges overlapping and cemented together. 50 Where two continuous sheets are used, as above described, there are three joints provided other than the extremities of the insulating unit, and the cementing together of the sheets is begun 55 at the central joint.

Instead of two continuous sheets an outer continuous sheet and four inner sheets may be employed, or as an alternative construction each slab may be wrapped independently and a single backing sheet employed for holding them together in the manner shown. The slabs being properly wrapped and secured together are applied to the cabinet with the slab 14 resting on top of the liner, the slabs 16 and 17 at the sides and the slab 15 at the bottom. The free ends of the slabs 15 and 17 are united by means of an adhesive tab 18. Thus continuous insulation for the two sides, top and bottom of the cabinet is provided.

In order to accommodate insulation for the rear of the cabinet the slabs 14, 15, 16, and 17 are beveled at their rear edges in order to receive a complementarily beveled rear slab 19. When the slab 19 is applied the joint around the margin of the same is sealed by gummed strips applied therover.

From the above it will be readily apparent that insulation for the cabinet with the exception of the door is formed of two units, one serving to insulate the top, bottom and two sides, and the second to insulate the rear. The cabinet is provided with two openings, one being the door at the front of the cabinet and the other being the window 20 in the rear wall of the cabinet, the wrapping for the insulation being sealed around the window opening.

Insulation constructed as above described and formed of two major sections can be easily applied with minimum labor.

It will be apparent to those skilled in the art

that various other changes may be made in the construction and arrangement without departing from the spirit of the invention, and therefore the invention is not limited to that which is described in the specification and shown in the drawings, 5 but only as indicated in the appended claims.

What is claimed is:

1. In a refrigerator cabinet having an outer casing and a storage compartment formed by a substantially rectangular liner within and spaced from said outer casing, insulation attached directly to the outside of said liner and comprising a plurality of slabs of insulation material hinged together by flexible, thermal insulating material.

2. In a refrigerator cabinet having an outer 15 casing and a storage compartment formed by a liner within and spaced from said outer casing, insulation attached directly to the outside of said liner and comprising a plurality of slabs of thermal insulating material connected by thin sheets 20 of flexible, thermally insulating material cemented thereto.

3. In a refrigerator cabinet having an outer casing and a storage compartment formed by a substantially rectangular liner within and 25 spaced from said outer casing, insulation attached directly to the outside of said liner and comprising a slab of thermally insulating material on each closed side of said liner, some of said slabs being hinged together by flexible, insulating 30 material, and the adjacent edges of all the said slabs being covered by thin flexible material.

CARL H. NAUERT.
